UNITED STATES PATENT OFFICE.

JOHN D. AUSTIN, OF THONOTOSASSA, FLORIDA.

MENDING-LINK.

SPECIFICATION forming part of Letters Patent No. 761,812, dated June 7, 1904.

Application filed October 6, 1903. Serial No. 175,919. (No model.)

To all whom it may concern:

Be it known that I, JOHN D. AUSTIN, a citizen of the United States, residing at Thonotosassa, in the county of Hillsboro and State of Florida, have invented a new and useful Mending-Link, of which the following is a specification.

This invention relates to devices employed for uniting sections of chains, either for connecting two separate chains or other similar devices or for mending broken chains, and has for its object the production of a simply-constructed and easily-applied device by which the adjacent ends of two chains or similar devices or the adjacent ends of two sections of a broken chain may be readily connected without detaching the chain; and the invention consists in certain novel features of the construction, as hereinafter fully described and claimed.

In the drawings illustrative of the invention, Figure 1 is a side elevation of the improved mending-link applied. Fig. 2 represents the two parts of the device in perspective and disconnected. Fig. 3 is a view similar to Fig. 1, illustrating a modification in the construction.

In a mending-link and similar devices as heretofore constructed one class requires the removal of the chain to a blacksmith-shop to enable the mending-link to be heated before insertion, while another class requires to be "cold shut" by the application of a bending force to the link. The first requirement is often a very expensive and troublesome one, especially when the forge is remote from the locality where the chain is employed, entailing long delay and serious interference with work, and the other requirement necessarily requires the employment of comparatively soft and malleable links, either of less strength than the other links of the chain if of the same size or of larger size if of the same strength.

In chains employed upon chain or sprocket wheels the links must necessarily be of the same size and of uniform interior diameter, and a mending-link to be employed in a chain of this character must therefore correspond both in size and location when in action to

the other links of the chain to cause it to run 50 with the other links in proper order upon the teeth of the wheel.

Another essential requirement of a mending-link capable of employment upon chain or sprocket pulleys is that it must conform 55 substantially in weight with the other links, so that the "balance" of the chain shall not be disturbed or produce unequal action.

All of the above requirements are fully met in the improved mending-link herein disclosed, which consists of twin separable members approximately L-shaped, the long arm 10 of each member being straight and terminating in an eye 11 and the short arm 12 bowed or curved outwardly, as at 13, intermediate of its length to form a seat centrally of the mending-link for the engaging links 14, as shown, so that when the draft is applied the adjacent engaging links of the chain (indicated at 14) will be certain to be seated in 70 the hollows in the short arms and insure a direct draft upon the stronger parts of the L-shaped members and prevent lateral strains against the members at their juncture with the tenons and all danger of the separation of 75 the two parts forming the mending-link obviated. The bars being made of a substantially uniform diameter throughout provide for a forging which is cheap to manufacture and which has no projections to engage passing objects and be broken. It will here be noted that the outer end of the seat terminates at the inner edge of the adjacent tongue 15, whereby the seat does not have any projected unbraced portions liable to become broken 85 under the action of strains and blows.

The short arms 12 are provided with terminal tongues 15, reduced in size, whereby shoulders 16 are formed at the base of the tongues, the tongues being disposed perpendicular to the long arms 10.

The outer portions of the eyes 11 are slightly "flaring," as shown, to provide for the riveting or upsetting of the outer ends of the tongues after insertion in the eyes to prevent 95 their removal.

The extremities of the long arms 10 are extended inwardly, as at 17, to form projections

over the adjacent portions of the short arms 12 to reinforce them and relieve the tongues 15 from a large portion of the strains.

The arms 10 12 may be constructed to 5 form substantially in area with the links of the chain into which they are connected, as by means of the novel construction herein shown. The mending-link is fully as strong, if not stronger, than the other links. Hence the 10 mending-link does not enlarge the chain at the points where introduced or change its general contour or length.

It will be noted that the distance between the short arms 12 of the mending-link is the 15 same as the end portions of the links 14 with which it is engaged, while the distance between the long arms 10 is the same as between the side portions of the engaged links, so that when connected into a chain all the links 20 respond, as heretofore described. By this arrangement the engaged links 14 will automatically seat themselves centrally in the bowed portions 13 and not contact when under strain with the long portions 10.

25 In Fig. 3 a slight modification in the construction is shown, consisting in forming one of the shorter arms 12 longer than the other, so that when connected the interior of the mending-link has a larger area at one end than 30 at the other. This form will be employed for connecting a draft-hook or similar member to the end of a chain, such members being necessarily larger than ordinary chain-links to resist the tendency to straighten out under

strains. This is an important feature of the 35 invention and adds materially to its value and efficiency and also its scope and increases its utility.

Another important advantage of the construction of mending-link herein disclosed is 40 that this link is stronger than the ordinary links of the chain or the broken link which it displaces, so that no loss of strength occurs by employing the improved link or connecting one or more chains or sections of chains 45 and without increasing the general size of the chain at the point where the improved link is inserted. This is a very important consideration in devices of this character and adds materially to its value and operativeness. 50

Having thus described the invention, what is claimed is—

A mending-link comprising twin separable members each of which consists of an approximately L-shaped member terminating in an 55 eye, the short arms terminating in reduced tongues disposed perpendicularly to the line of the long arms and with shoulders formed at the base of said tongues, the terminals of said long arms being extended inwardly over 60 said short arms to reinforce the same.

In testimony that I claim the foregoing as my own I have hereto affixed my signature in the presence of two witnesses.

JOHN D. AUSTIN.
